SHOE AND SHANK STIFFENER THEREFOR

William H. Nickerson, Newton Center, Mass.

Application August 4, 1937, Serial No. 157,337

8 Claims. (Cl. 12—142).

This invention relates to shoe manufacture and is particularly concerned with shoes having stiffeners or arch supporters in the shank portion of their bottoms. Its object is to provide a means by which a better anchorage may be obtained for the cements and adhesives which, in some makes of shoe, are applied between the shank stiffener and the inner or outer sole, and by which to eliminate or minimize squeaking when the shoe is flexed with movements of the wearer's foot in walking. These objects are accomplished by providing metallic shank stiffeners, arch supports, and the like, which may otherwise be of standard materials, dimensions and shape, or of any other suitable shapes, with a multiplicity of small low protuberances on at least one surface, and in at least the mid portion of the length of such surface, which protuberances are adapted to bear on their summits against the adjacent surfaces of one of the soles (outer sole or innersole) of the shoe; in providing a network of shallow channels between and around such protuberances adapted to receive and confine cement; and in effecting such an engagement between the so-treated side of the stiffener or support in the adjacent surface of a shoe sole, as to expel the cement wholly or in large measure from between the protuberances and the adjacent sole, causing the protuberances to emerge from the cement covering and forming narrow flexible ridges of cement adhering to the shoe sole surface and occupying the channels between the protuberances. The invention consists in a shoe having a shank stiffener or arch support of the character indicated; the combination between such a stiffener, the adjacent shoe sole and interposed ridges of cement; the new shank stiffener constituting a part of such a combination; and the method of combining the stiffener and sole in a shoe in such manner as to achieve the desired objects.

The drawing furnished herewith shows an illustrative embodiment of the invention and the parts thereof.

Fig. 1 is a side view of a shoe, partly broken away to show its bottom in longitudinal section, containing the shank construction of this invention;

Fig. 2 is a side elevation of the shank stiffener shown in Fig. 1;

Fig. 3 is an under plan view of the same shank stiffener;

Fig. 4 is a view similar to Fig. 3 of another type of shank stiffener, which is also sometimes called an arch support, embodying the invention;

Fig. 5 is a longitudinal section of a fragment of

the shank portion of the shoe bottom shown on an enlarged scale with exaggeration of the width and depth of the channels between the surface protuberances of the stiffener to illustrate in principle the manner in which contact between the stiffener and sole is limited and cement is disposed in interlocking engagement with the protuberances;

Fig. 6 is a cross section through the shank portion of the shoe bottom on the line 6—6 of Fig. 5 and shown on the same exaggerated scale.

Like reference characters designate the same parts wherever they occur in all the figures.

The shoe here illustrated has an innersole *a*, an outer sole *b* and a shank stiffener *c* placed between the inner and outer soles and made fast to the former at one or both ends by a tack or tacks *d*, *d*, or other suitable fastening means, such as integral prongs, etc.

The shank stiffener *c* is given a longitudinally curved or arched shape corresponding to that of the shoe with which it is designed to be used, and it is transversely curved with a trough-like formation which makes it convex on one side and concave on the other. Such transverse curvature exists in varying degrees in the major part of the length of the stiffener but diminishes and disappears at and near the extremities. Such stiffeners are customarily cut from flat strip or sheet steel and brought into final form by pressing and bending between suitable dies.

The stiffener is embossed on the side which provides the transversely convex formation so as to make numerous protuberances or humps *e*, located near to one another, but at the same time distinctly spaced apart and separated by intermediate channels or depressions. These projections and channels are most practicably produced by passing the strip or sheet steel, in the final step of rolling to final thickness, between rolls of which one has a suitably engraved or pitted surface. When the stiffener blanks are grooved and offset, the embossed side is placed next to the concave grooving die, whereby in the finished stiffener the embossments or protuberances are caused to lie on the convex side. Such protuberances lie beside one another throughout the entire width of the stiffener.

The outlines of the protuberances and their disposition with respect to one another may be regular or irregular, and their contours in profile may be rounded or abrupt in any desired measure. Those in the specimens from which the illustrations in the present drawing were made are nearly flat on the summits and have steep declivities at

their sides, such that their areas at the summit are but little, if at all, larger than at the base. They are more or less irregular and unequal in outline and dimensions, the average of their 5 length and width dimensions being in the order of from one to three thirty-seconds of an inch. The depth of the intermediate valleys or channels is very small, being in the order of a few thousandths of an inch, which is but a small fraction 10 of the thickness of the stock from which stiffeners are made. These dimensions, however, are not limiting but 15 illustrative, and may be considerably varied within the scope of the invention, provided the depressions are not so deep as to weaken the stiffener or requiring it to be made objectionably heavy in order to have the necessary strength, or 20 deep enough to mold ridges of cement so thick as to be brittle when dry.

20 Contact between the convex side of the stiffener and the adjacent shoe sole, (in the illustrated case the outer sole), is limited to the summits of the projections. Hence the areas of contact are 25 small and separate from one another, but numerous. They are so narrow also that two or more points of contact are found in nearly every transverse section of the shank. I have found in practice that with this construction there is substantially complete elimination of squeaking due 30 to rubbing of the embossed surface of the stiffener on the adjacent surface of the shoe sole with the movements of the wearer's foot in walking.

When cement is used between the stiffener and sole, the latter is pressed and held against the 35 stiffener with such force as to cause the projections to penetrate the cement coating and substantially expel cement from between their summits and the contiguous surface of the sole. When the cement occupying the channels between the 40 projections sets or dries to solid condition it interlocks with the projections and more securely retains the stiffener against displacement than is done by adhesion alone. The interlocking ridges of cement thus formed are so low in 45 height, due to the shallowness of the channels, that they remain flexible even when hard and dry and retain their efficiency as mechanical locking projections independently of the bond due to adhesion alone, which latter may be soon broken.

50 The condition in which the cement exists, is illustrated in an exaggerated way in Figs. 5 and 6. The protuberances *e* bear closely against the inner surface of the outer sole, and may even indent this surface to some extent. The cement lies in the form of irregular projections *f* occupying the channels between the protuberances of the shank stiffener. The condition thus illustrated and described is that in the tangent zone between the convex side of the stiffener and the adjacent surface of the outer sole. The condition 55 of the cement at either side of this zone is unimportant, for it is only at the contact zone, of course, that squeaking due to rub of the stiffener on the outer sole can occur, and it is here that the ridges of cement perform their intended function.

70 The same essential invention may be embodied in shoes of all sizes and styles which have shank stiffeners, and in connection with stiffeners of other dimensions and contours.

An illustration of such another stiffener is given in Fig. 4 of the drawing where a so called arch support *g* is shown. This arch support is applied to the shoe in the same manner as the 75 stiffener *c*. Like the latter it is bowed longi-

tudinally and is made concavo-convex transversely. But it is wider and is so bulged near its forward end as to form a hump *h*, the hollow side of which provides a pocket in which a pad may be placed to support the metatarsal arch of the foot. The invention may likewise be embodied in shoes where the convex curvature of the stiffener is turned toward the innersole; in flat stiffeners; in so called composite shanks composed of a leather or fiberboard body piece and a steel reinforcing strip, and in arch supports which are worn inside of shoes to support fallen arches of the wearer's feet.

An equivalent embossed or pebbled configuration may be applied to the mid length part only of the shank stiffener instead of throughout the entire length thereof, if desired, for it is in the middle portion particularly that the need and utility of this configuration exists. By "middle portion" in this explanation I mean so much of the length as constitutes a major part thereof but terminates short of either or both ends as, for example, so much of the length of the stiffener as is comprised between the points *k* and *l* in Fig. 2.

The shank stiffener herein described was first disclosed in my prior application filed June 13, 1936, Serial No. 85,104, of which the present application is a continuation as to that subject matter.

What I claim and desire to secure by Letters Patent is:

1. The process of shoe making which comprises providing a shank stiffener having an embossed surface with shallow channels between and around the embossments, applying cement between the embossed surface of such stiffener and the surface of a sole of the shoe, and applying the sole with pressure between it and the stiffener such that the embossed projections of the latter penetrate substantially through the cement coating into contact with the adjacent surface of said sole, leaving ridges of cement in the channels.

2. In the manufacture of a shoe, the steps of providing a metal shank stiffener having an embossed surface with shallow channels, the depth of which is in the order of a few thousandths of an inch, between and around the protuberances of such embossed surface, laying a sole and an interposed layer of cement against the embossed side of such stiffener so that the protuberances of the latter pass substantially through the cement layer into contact with the surface of the sole, and holding the sole and stiffener together during setting of the cement.

3. In shoe making, the steps of applying to the bottom of a lasted shoe, prior to application of the outer sole, a metal shank stiffener having an embossed surface with shallow channels between the protuberances, applying a layer of cement to the embossed surface of the stiffener, and pressing an outer sole against the cemented stiffener so that the protuberances of the latter penetrate substantially through the cement into contact with the outer sole and the cement, after drying, forms a network embracing the projections of the embossed stiffener.

4. A shoe including in its construction a sole and metallic shank stiffener, said shank stiffener having its surface next to the sole formed with embossments and intermediate valleys of a depth which is but a small fraction of the thickness of the stiffener, and being in contact with the adjacent surface of the sole only at the summits of such embossments, and the sole having ad-

herent ridges of cement occupying channels and embracing projections of the embossed stiffener.

5. A shoe including a sole and a metal shank stiffener or arch support, said stiffener having in its surface next to the sole a network of communicating narrow and shallow channels, and the adjacent surface of the sole having ribs of cement molded in said channels and of such small height as to be non-brittle and flexible.

10 6. A metal shank stiffener or arch support for use in shoes having in one surface a network of connected channels of narrow width and a depth which is a small fraction of the thickness of the stiffener, such channels being adapted to form a

15 matrix for cement ridges when applied to the surface of a shoe sole against an interposed layer of cement, and the material of the stiffener between the channels providing a multiplicity of contact areas.

20 7. A metal shank stiffener or arch support for use in shoes, having on one face a multiplicity of low protuberances separated from one another by

intermediate valleys or channels, the summits of such protuberances being smooth and of nearly as large area as their bases and of such small area that a plurality of them are adapted to bear on the surface of an adjacent shoe sole both lengthwise and transversely of the stiffener. 5

8. A metal shank stiffener or arch support for use in shoes, having on one face a multiplicity of low protuberances separated from one another by intermediate valleys or channels, the summits of such protuberances being smooth and of nearly as large area as their bases and of such small area that a plurality of them are adapted to bear on the surface of an adjacent shoe sole both lengthwise and transversely of the stiffener, such 10 channels being adapted to receive cement when the stiffener is pressed against a cement coated shoe sole, and their depth being in the order of a few thousandths of an inch whereby the ribs of such cement molded therein are non-brittle 15 and flexible after setting. 20
